UNITED STATES PATENT OFFICE.

ALFRED KOHLBERG, OF BRONXVILLE, NEW YORK.

DESIGN FOR AN EMBROIDERED TABLECLOTH OR SIMILAR ARTICLE.

Application filed September 7, 1927. Serial No. 23,314. Term of patent 3½ years.

To all whom it may concern:

Be it known that I, ALFRED KOHLBERG, a citizen of the United States, residing at Bronxville, in the county of Westchester and State of New York, have invented a new, original, and ornamental Design for Embroidered Tablecloth or Similar Article, of which the following is a specification, reference being had to the accompanying drawing, forming a part thereof.

The figure is a plan view of a quarter section of an embroidered tablecloth, showing my new design, the representative illustration being repeated in the other three quarters of the tablecloth.

I claim:

The ornamental design for an embroidered tablecloth or similar article, as shown and described.

ALFRED KOHLBERG.
